UNITED STATES PATENT OFFICE

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA

SOUND PRODUCER

Application filed December 18, 1928. Serial No. 326,733.

This invention relates to audible signal devices and more particularly to pneumatically operated sound producers.

An object of the invention is to provide a sound producer in which means are provided for closing the mouth of the horn when the device is silent.

Another object of the invention is to provide a sound producing device with a closure for the mouth of the horn of the device, which closure is automatically opened and closed by mechanism actuated by the sound producing means.

Another object of the invention is to provide a sound producer of the character mentioned which is relatively simple in construction, and reliable and exact in function under all conditions of service.

The invention also comprises certain new and useful improvements in the construction, arrangement and combination of the several parts of which it is composed, as will be hereinafter more fully described and claimed.

In the accompanying drawings: Figure 1 is a side elevation, partly in section, of a sound producing apparatus embodying the invention, the closure for the mouth of the horn being shown closed; Fig. 2 is a front view; Fig. 3 is a plan of the forward portion 30 of the structure shown in Fig. 1; and Fig. 4 is a view similar to Fig. 3, showing the closure open.

Referring to the drawing, the sound producing apparatus may comprise a casing 1 having a chamber 2 which is open to a flexible diaphragm 3 mounted in the end of the casing.

The casing 1 is provided with a threaded opening at the side opposite the diaphragm 3 into which is screwed a resonance tube 4. This tube has an enlarged portion 5 forming a shoulder adapted to engage the end face of the threaded portion of the casing 1.

Secured to the tube 4 is a suitable amplifying horn 6.

When the tube 4 is screwed down so that the shoulder thereof engages the end of the threaded portion of the casing, the free end of the tube just engages the diaphragm 3.

Secured to the central portion of the dia-

phragm 3 and extending into the open end of the tube 4 is a weight 7.

Spaced from, and enclosing the side of the diaphragm 3 opposite to the weight 7, is a cover plate 8 provided with an opening 9 so that the chamber at the outer face of the diaphragm 3 remains at atmospheric pressure at all times.

The chamber 2 is connected by a restricted opening 10 to a conduit or passage 12 leading to a cylinder 11.

Contained in the cylinder 11 is a piston 13, which is subject on one side to the pressure of an expansible spring 14, and which is subject on the other side to fluid under pressure in a chamber 15.

The spring side of the piston 13 is provided with a stem 16 which is slidably mounted in a tubular boss 17 projecting inwardly from the end wall of the cylinder 11.

The projecting end of the boss 17 is formed with a seat ring 18 against which the seat 19 of the piston 13 engages, when the piston is moved outwardly in the manner to be described.

The chamber 15 is connected to a pipe 20, through which fluid under pressure is supplied to said chamber, the amount of fluid flowing through the pipe being controlled by means of the plug valve 30 of an angle cock 21.

The piston stem 16 projects beyond the end of cylinder 11 and its projecting end carries a crosshead 22 to which are connected the inner ends of a pair of links 23.

The forward ends of the links 23 are pivotally connected, at 24, to the arms 25 of a pair of shutters 26 mounted on the flaring mouth of the horn 6 by suitable hinges 27.

As shown, the shutters 26 may consist of two semi-circular plates which are adapted to close the mouth of the horn when the device is inoperative, or silent, so as to prevent the entrance of snow and ice, water, dirt, and other foreign matter into the horn, which ordinarily have a tendency to render the sound producing elements inoperative.

In operation, when the plug valve 30 is turned to connect the waterway or port 31 with the pipe passage, fluid under pressure will be supplied to the chamber 15, building

up a pressure to move the piston 13 outwardly, against the force of the spring 14, and seal the same against the seat ring 18.

When the piston is moved outwardly, the shutters 26 will be opened through the mechanism connecting the arms 25 of the shutters with the piston crosshead 22, thereby uncovering the mouth of the horn 6. Such shutters will remain in open position as long as the piston 13 is seated against the seat ring 18 by the pressure of the fluid in chamber 15.

When the piston 13 is seated against the seat ring 18, port 33 will be uncovered and the fluid supplied to chamber 15 flows through the conduit 12 and the restricted opening 10 into chamber 2, and the pressure of fluid in chamber 2 builds up so that the diaphragm 3 is moved outwardly.

In moving out, communication is opened from chamber 2 to the space within the tube 4. The pressure in said chamber is then quickly reduced, since the rate of flow through restricted port 10 is considerably less than the rate of flow from chamber 2 to tube 4. The pressure on the diaphragm 3 being thus relieved, said diaphragm returns to its position engaging the end of the tube 4. The opening movement is then repeated.

The diaphragm 3 is thus caused to vibrate and thereby produces a sound which is amplified by the usual operation of the horn 6.

The addition of the weighted member 7 to the diaphragm 3 makes it necessary for the fluid pressure to be built up to a higher point before the diaphragm will move from engagement with the end of the tube 4, than would be the case with an unweighted diaphragm, but when the diaphragm does move, the higher pressure causes a greater movement of the diaphragm and consequently, a greater amount of potential energy is stored up, so that the return movement of the diaphragm is effected more forcibly. A more positive opening and closing movement of the diaphragm is thus assured.

An opening 34 is formed through the piston 13, and chamber 35 on the spring side of the piston is open to atmospheric pressure through a leakage groove 36.

When the plug valve 30 is operated to shut off the supply of fluid to the chamber 15, the spring 14 returns the piston 13 to its normal position, as shown in Fig. 1, and this action will close the shutters 26, as will be readily understood. The opening 34 insures that the piston 13 will return to its normal position. However, said opening enables the piston to release slow enough to permit the shutter to remain open for a short time, as occurs when a series of short blasts are to be produced by the sound producing apparatus.

While one illustrative embodiment of the invention has been described in detail, it is not my intention to limit its scope to that em-

bodiment or otherwise than by the terms of the appended claims.

Having now described my invention, what I claim as new and desire to secure by Letters Patent, is:—

1. A device of the class described comprising sound producing means, a horn, movable closure elements for closing the horn when the sound producing means are inoperative, and means actuated by the sound producing means for actuating the closure elements. 70 75

2. A pneumatically operated sound producer having a horn provided with a pivoted shutter for closing the horn when the sound producer is inoperative, means for supplying fluid under pressure to the sound producer, and fluid pressure sensitive means for actuating the shutter when the fluid is being supplied to the sound producer. 80

3. A device of the class described comprising fluid operated sound producing means having a horn provided with shutters which normally close the mouth of the horn, a cylinder containing a piston, links connecting the piston and the shutters, said cylinder being in communication with the sound producing means when the piston is at one end of its stroke, and means for supplying fluid under pressure to the cylinder to cause the piston to move to the position in which fluid will be supplied to the sound producing means. 85 90 95

4. The combination with a sound producing means operated by fluid under pressure and a horn associated therewith, of means normally closing the horn outlet and operated to open the horn outlet upon supplying fluid under pressure to said sound producing means. 100

5. The combination with a sound producing means operated by fluid under pressure and a horn associated therewith, of a shutter for controlling the outlet of the horn, and means operated by fluid under pressure for operating said shutter. 105

6. The combination with a sound producing means operated by fluid under pressure and a horn associated therewith, of a shutter for controlling the outlet of the horn, and means operated by fluid under pressure for operating said shutter and for controlling communication through which fluid under pressure is supplied to said sound producing means. 110 115

7. A device of the class described comprising sound producing means having a horn provided with fluid operated means for closing the horn when the device is inactive. 120

8. The combination with sound producing means and a horn associated therewith, of fluid operated means for closing the horn outlet when the sound producing means is inactive. 125

In testimony whereof I have hereunto set my hand, this 17th day of December, 1928.

CLYDE C. FARMER. 130
